DESIGN FOR AN UPHOLSTERY AND DRAPERY FABRIC

Samuel J. Oliver, East Orange, N. J.

Application September 12, 1933. Serial No. 49,237

Term of patent 3½ years

To whom it may concern:

Be it known that I, SAMUEL J. OLIVER, a citizen of the United States of America, residing at East Orange, Essex County, State of New Jersey, have invented a new, original, and ornamental Design for Upholstery and Drapery Fabric, of which the following is a specification, reference being had to the accompanying drawing, forming a part thereof and in which:—

The figure is a plan view of a fragmentary portion of a fabric showing my new design in its upper portion and an indication of repetitions of the same by broken lines in the lower portion.

I claim:—

The ornamental design for upholstery and drapery fabric, as shown and described.

SAMUEL J. OLIVER.
